UNITED STATES PATENT OFFICE

CLINTON DE WITT, OF SAN FRANCISCO, CALIFORNIA, ASSIGNOR TO TAPER TUBE POLE CO., OF SAN FRANCISCO, CALIFORNIA, A CORPORATION OF CALIFORNIA

DESIGN FOR AN ELECTROLIER

Application filed October 29, 1929. Serial No. 33,203. Term of patent 14 years.

To all whom it may concern:

Be it known that I, CLINTON DE WITT, a citizen of the United States, residing at the city and county of San Francisco, State of California, have invented a new, original, and ornamental Design for Electroliers, of which the following is a specification, reference being had to the accompanying drawings, forming part thereof.

Fig. 1 is a front view of the electrolier, and Fig. 2 is a cross section of the center portion of the electrolier.

I claim:
The ornamental design for an electrolier, substantially as shown.

CLINTON DE WITT.
